UNITED STATES PATENT OFFICE.

SAMUEL SUEKOFF, OF CHICAGO, ILLINOIS.

SPRING-CUSHION CONSTRUCTION.

Application filed July 6, 1925. Serial No. 41,466.

This invention relates to improvements in spring cushion construction, and more particularly to an efficient and economical method of fabricating and assembling spring 5 cushions.

As commonly made, a spring cushion consists of pieces of fabric usually burlap, cut and sewn together not only to form the bottom, top and side walls, but a series of 10 individual cells or pockets within the outer walls, and adapted to contain the springs. The problem of making spring cushions is not so much one of structure as it is one of method of preparing the material for sewing, and then sewing the pieces together, so 15 that the cushion can be loaded with springs, with the least amount of time and labor.

The object of the present invention is therefore, to provide a method of further 20 reducing the labor cost of cushion construction, attention being called to the fact that in the present highly competitive state of the spring-cushion industry, an unprofitable business may become profitable by an apparently inconsequential saving in the item of 25 labor costs. Thus, the elimination in one step of the manufacturing process, or the completion of two steps in a single operation, or a more efficient treatment of the 30 material in preparation for assembling, would be important to the manufacturer in meeting competition.

Of such a nature is the present invention and its applicability to the art will be better 35 appreciated as the process is disclosed with the aid of the accompanying drawings, in which—

Figure 1 is a perspective view showing the first step of assembling the material 40 which forms one of the covers and a portion of the internal structure of the cushion.

Figure 2 is a similar view of the piece shown in Figure 1, after it has been cut, as the second step in the process.

Figure 3 is a perspective view of the piece shown in Figure 2 with the partition walls in place, as the third step.

Figure 4 is a top plan view of the finished cushion with portions broken away to show 50 the interior construction.

Figure 5 is a detail view in vertical section taken on line 5—5 of Figure 4 and

Figure 6 is a similar view taken on line 6—6 of Figure 4.

Regarding first the structure of the cushion as a whole, the same consists of top and

bottom pieces 1 and 2, of suitable fabric, such as burlap, sewn together at their edges in a seam 3 extending around the cushion between the top and bottom thereof, the 60 marginal portions of these pieces forming the "boxing" or end and side walls of the cushion.

Within the outer covering formed by the pieces 1 and 2, are a series of continuous 65 partition strips 4 extending the full length (or width) of the cushion, with the longitudinal edges sewn to the top and bottom cover pieces. These partition strips are parallel 70 with each other and divide the interior space of the cushion into a plurality of full length compartments.

These compartments formed between the partition strips 4, and between the outer of 75 such strips and the parallel end (or side) walls of the cover, are divided lengthwise into a plurality of smaller compartments or cells, by means of vertical division walls or tabs 5, extending at right angles to the partition strips. These division walls 5 are arranged in rows either lengthwise or cross- 80 wise of the cushion, with just sufficient space between their adjacent side edges to clear the partition strips 4. These tabs are stitched at one end to the bottom piece 2, 85 and at their other ends to so-called connecting strips 6 which lie flatwise against the top piece 1 and extend parallel with the partition strips and between their upper edges. As a preferable construction, only 90 one edge of the connecting strips are sewn to top pieces, namely, by a single line of stitching, which serves to attach both the edge of the connecting strips and the edge of the adjacent partition strip 4 to the top 95 cover piece leaving the opposite edge free, as will presently be described in detail.

In the actual process of manufacture, one side of the cushion is left open or unsewn for the insertion of the springs 7. These 100 springs are helical coils of wire, of a length equal to the height of the finished cushion, and are adapted to stand upright under slight compression within each of the small compartments or cells. As a preferable 105 method of loading the cushion with springs, an implement known as a loading tool is used in which a number of springs equivalent to the number constituting a single row, are held flatly compressed within the tool, 110 which is inserted into the open end of the cushion and along one side of each longi-

tudinal compartment formed between successive partition strips, the tool being held so that the flattened springs pass through the openings between the partition strips 5 and the adjacent edges of the tabs. As a preferable method, the tool is inserted along what is called the "tight" side of the spring compartments, that is, the side adjacent the stitched edges of the connecting strips 6, 10 the opposite edge being the "loose" side so-called because the free or unsewn edges of the connecting strips secure the tabs 5 to the top piece 1 at one end only.

The primary advantage is the provision 15 of the connecting strips 6 which serve as intermediate members not only joining the tabs at one end indirectly to the adjacent cover member, but affording the loose construction that permits the flexibility that is 20 essential to rapid, and convenient loading of the cushion with springs.

Having thus disclosed generally the structure of the cushion and the method of spring loading, the process for forming and assembling the material for the cushion will now 25 be described, bearing in mind that reference to the top and bottom of the cushion serves only to make the description clear.

As the first step in the process, two rectangular pieces of fabric are first provided, 30 one being the bottom cover piece 2, and the other an unsevered piece 6^a which ultimately is converted into the connecting strips 6. These pieces lie in parallel planes with a 35 series of parallel strips 5^a extending transversely between them with their edges stitched to said pieces 2 and 6^a as shown in Figure 1.

This assembled structure is then applied 40 to a suitable frame which holds or stretches the several pieces taut, as they appear in Figure 1. Thus stretched the assembly is subjected to a cutting or slitting process whereby gang cutters act to sever the upper piece 6^a and the strips 5^a transversely of 45 their length down to the bottom piece 2, but leaving the latter intact, as shown in Figure 2. In this way the unsevered piece 6^a is converted into the connecting strips 6 and 50 the strips 5^a into the individual tabs 5 by a single cutting operation. The obvious advantage of this method is that tab forming strips 5^a can be stitched to an unsevered piece of fabric, and then cut by one operation 55 into the connecting strips and tabs, with much less labor than sewing the ends of each individual tab first to a connecting strip and then sewing the other ends separately to the bottom piece, all of which is a 60 very tedious and time consuming operation.

Having thus provided the bottom piece 2 with the tabs 5 and connecting strips 6 stitched thereto, as shown in Figure 2, a series of partition strips 4, are inserted along 65 the rows of slits 5^b between the tabs, and

their lower edges sewed down to the bottom piece, along the base of the slits, by a line of stitching 4^a as shown in Figure 3, the upper edges of the strips extending above the connecting strips and providing a marginal portion or hem 4^b which is later sewn down as will be presently described. The next step is to apply the top piece 1, over the connecting strips 6 and stitching it down, one edge being sewn to the bottom piece at 70 3 as shown in Figure 5, and then working from the same edge, sewing the successive connecting strips to the top piece, by 75 stitches 8.

It is to be particularly observed that the 80 single lines of stitching 8 are used for this purpose, which extends along one edge of each connecting strip, namely, along the left hand edge as shown in Figure 4. It is to be also observed that the hem or marginal portion 4^b of each partition strip, is folded over upon the edge of each adjacent connecting strip, so that the single line of stitching 8 also secures these margins in place, between the top piece and the connecting strips, thus passing through three thicknesses of the fabric; thus the pieces are all assembled and sewn together with the upper ends of the tabs 5, stitched to the connecting strips 6, which are only fixed to 90 the top piece along one edge, the remaining portion being loose, for convenience in loading, but which assumes an extended position as soon as the springs are inserted, and the cushion completed.

As before explained, this process of assembling of unsevered pieces and strips to form the connecting strips and tabs, by a gang cutting process, but without severing the bottom piece, results in a marked saving 105 of time and labor in the manufacture of spring cushions, the reason being that it eliminates the sewing of a multitude of short seams, each of which is a separate sewing operation.

I claim as my invention:

1. A method of constructing spring cushions, consisting of providing two pieces of material, connecting them by a series of parallel strips extending at right angles to said pieces, holding said assembled pieces taut and cutting one of said pieces and said strips along parallel lines transverse to said strips and down to the other piece, and applying a piece corresponding to said unsevered piece over said severed piece and sewing one edge of the strips of said severed piece to said last mentioned piece.

2. A method of constructing spring cushions consisting of assembling two pieces of fabric with a series of parallel strips extending transversely between said pieces, slitting one of said pieces and said strips crosswise of the latter down to the other piece to form a series of connecting strips and relatively

narrow tabs, inserting a partition strip between each row of tabs and stitching the same to the unsevered piece along one of their edges, applying a cover piece over said 5 connecting strips and stitching one edge of each connecting strip thereto together with the adjacent free edges of each partition strip.

3. A method of constructing spring cushions consisting of assembling two pieces of 10 fabric with a series of parallel strips extending transversely between said pieces, stretching said assembled pieces in extended

form; and slitting the same crosswise of said strips down to the base edges thereof, inserting partition strips along the slits and sewing their base edges to the unsevered piece, applying a cover piece over the severed piece of said assembly, and sewing the same along parallel lines of sewing to the free edges of 20 said partition-strips and the severed piece adjacent each slit therein.

Signed at Chicago, Ill., this 3 day of July, 1925.

SAMUEL SUEKOFF.
